UNITED STATES PATENT OFFICE.

GEORGE W. WEIMER, OF GIRARD, OHIO.

REPEATER TERMINAL FOR ROLLING MILLS.

Application filed January 30, 1923. Serial No. 615,893.

To all whom it may concern:

Be it known that I, GEORGE W. WEIMER, a citizen of the United States, residing at Girard, in the county of Trumbull and State of Ohio, have invented certain new and useful Improvements in Repeater Terminals for Rolling Mills; and I do declare the following to be a full, clear, and exact description of the invention, such as will enable others skilled in the art to which it appertains to make and use the same.

My invention relates to improvements in rolling mill attachments and has reference more particularly to mills of the type having work returning guides, commonly known as repeaters, for returning the work from one set of rolls to the next. Under the present day methods of rolling strips and bars in mills of the type set forth, it is necessary to manually guide the work from the repeater to the next set of rollers and it often happens that in traveling through the repeater, the work becomes twisted to some extent, making it extremely difficult for the attendant to properly guide this work to the rollers. It is the object of my invention however to provide a simple and inexpensive, yet an efficient and reliable terminal for the repeater or work returning guide, which will not only guide such work to the next set of rolls, but will straighten the work if it has been twisted while making the return bend from one set of rolls to the next. In carrying out this object, a further aim is to provide a terminal which will be laterally expansible to some extent to permit it to accommodate work of different sizes and to enable the work to be easily removed in case it should by any possibility become jammed.

With the foregoing in view, the invention resides in the novel subject matter hereinafter described and claimed, the description being supplemented by the accompanying drawings.

Figure 1 is a plan view showing the application of the terminal to a rolling mill.

Figure 2 is a side elevation of the terminal.

Figure 3 is a central vertical longitudinal sectional view.

Figure 4 is a horizontal sectional view on line 4—4 of Fig. 2.

Figure 5 is a vertical transverse sectional view through the terminal, adjacent the work receiving end thereof.

Figure 6 is a view similar to Fig. 5, on line 6—6 of Fig. 4.

In the drawings above briefly described, the characters R and R' designate the first and second sets of rolls of a rolling mill for forming strips and bars, and the letter G refers to the usual J-shaped repeater or guide which returns the work after it leaves the rolls R, in order that it may be guided into the rolls R'. Between the outlet end of the guide G and the inlet guide G' of the rollers R', the improved terminal T is located, this terminal being internally shaped to receive the work from the guide G and straighten it if it has become twisted and then direct it into the guide G'.

In the preferred form of construction, the terminal T is of the formation disclosed in Figs. 2 to 6. The numeral 1 designates a horizontally elongated base plate which is suitably connected at 2 with the outlet end of the guide G, a pivot being preferably provided at the point 2 in order that the outlet end of the terminal 30 may be properly alined with the guide G' under all circumstances. The rear end of the plate 1 is formed with a throat 3 which guides the work between a pair of elongated guiding and straightening members 4 which are mounted on the plate 1 and have their inner adjacent sides longitudinally grooved throughout their lengths, as indicated at 5, to form a guiding and straightening passage for the work. This passage 80 decreases in cross sectional area from its inlet to its outlet end and is helically directed to some extent as will be seen by comparing Figs. 5 and 6. Thus, if the work has been twisted to some extent while passing around the guide G, it will gradually 90 be straightened as it passes through the co-acting grooves 5.

I mount the members 4 in such a manner that they may be moved outwardly away 100 from each other to some extent, in order to accommodate them for the handling of larger work and in order that the work may be removed from the terminal, in case it should by any accident, become jammed. In 105 the preferred form of construction, the members 4 have lateral ears 6 pivoted at 7 to similar ears 8 on the rear end portions of the bed plate 1, so that the front ends of said members 4 may be swung outwardly as 110 required. I prefer to provide these members 4 with outstanding ears 9 near their

front ends which contact with the upper sides of slotted ears 10 on the bed plate 1, clamping bolts 11 being passed through the two sets of ears in order that the members 4 5 may be held rigidly after adjustment.

By the use of my invention, difficulties heretofore encountered are overcome in an expeditious manner and a device is provided which will be efficient and reliable and 10 will greatly save in labor and time.

As excellent results may be obtained from the details disclosed, they may be followed if desired. However, within the scope of 15 the invention as claimed, numerous minor changes may be made.

I claim:

1. A terminal for the work returning 20 guide of a strip rolling mill, comprising an elongated laterally expansible work receiving and straightening guide, closed at its sides and open at its ends, the interior of said guide decreasing in cross sectional area from its inlet to its outlet end and being helically formed to straighten the strip if 25 twisted in the work returning guide.

2. A terminal for the work returning 30 guide of a strip rolling mill, comprising a base plate having means for mounting it in operative relation with the return guide, a pair of elongated work guiding and straightening members on said base plate having their inner sides longitudinally grooved throughout their length to form a guiding and straightening passage for the work, 35 said passage decreasing in cross sectional size from its inlet to its outlet end and being helically formed to straighten the strip if twisted in the work returning guide, and means for mounting said members on said base and permitting lateral adjustment thereof.

3. A terminal for the work returning 40 guide of a strip rolling mill comprising a base plate having means for mounting it in operative relation with the return guide, a pair of elongated work guiding and straightening members on said base plate having their inner sides longitudinally grooved throughout their length to form a 45 guiding and straightening passage for the work, said passage decreasing in cross sec-

tional size from its inlet to its outlet end and being helically formed to straighten the work, means pivotally mounting the rear ends of said members on said base plate, and 55 means for adjustably securing the front ends of said members to said plate and for permitting lateral adjustment of said members.

4. In combination with a work returning 60 guide of a strip rolling mill, a terminal comprising a base plate mounted in operative relation with the return guide, a pair of elongated work-guiding members on said base plate having their inner sides longitudinally grooved throughout their lengths to form a guiding passage for the work, means pivotally mounting the rear ends of said members on said base plate, and means for adjustably securing the front ends of 65 said members to said plate and for permitting lateral adjustment of said members.

5. The combination with a pair of rolling 70 mills having reducing passes therein, of a horizontally disposed open trough return bend guide adapted to receive a strip from the passes of one mill and to reverse its direction towards the passes of the other mill and having a covered delivery end, a base plate pivoted to the end of the guide provided with a covered receiving end matching the delivery end of the trough, and a twisting guide for the strip mounted on the pivoted base for delivery to the receiving 75 passes of the mill.

6. The combination with a pair of rolling 80 mills having reducing passes therein, of a horizontally disposed open trough return bend guide adapted to receive a strip from the passes of one mill and to reverse its direction towards the passes of the other mill and having a covered delivery end, a base plate pivoted to the end of the guide provided with a covered receiving end matching the delivery end of the trough, 85 and a twisting guide for the strip composed of two co-acting sides adjustably mounted on the pivoted base and providing a guiding channel for the strip.

In testimony whereof I have hereunto 90 affixed my signature.

GEORGE W. WEIMER,
